UNITED STATES PATENT OFFICE.

CHARLES NEWTON, OF BUFFALO, NEW YORK.

FIRING-TRIGGER MECHANISM FOR FIREARMS.

Application filed June 27, 1924. Serial No. 722,727.

To all whom it may concern:

Be it known that I, CHARLES NEWTON, a citizen of the United States, residing at Buffalo, in the county of Erie and State of New York, have invented new and useful Improvements in Firing-Trigger Mechanism for Firearms, of which the following is a specification.

This invention relates to a firing trigger mechanism and more particularly to that class of firearms in which both a firing or releasing trigger is employed for operating the sear directly and also a firing hammer whereby the sear may be operated directly by a hammer blow upon pulling the main or firing trigger.

In this usual form of double trigger mechanism for firearms, as heretofore constructed, the main, releasing or firing trigger was located in front of a rear or set finger piece operating the firing hammer which necessitated reaching with the forefinger forwardly past the trigger of the firing hammer in order to properly engage the front or firing trigger. This is objectionable inasmuch as the knuckle of the second finger during this operation of the firing trigger by the forefinger is brought close to the rear end of the guard where it is liable to be injured by the recoil of the firearm, particularly in the event of a heavy recoil of the same. This old form of double trigger mechanism was also so constructed that both the main or firing trigger and the finger piece of the firing hammer are operated by a rearward pull or movement of the finger pieces which necessitated a separate finger space within the guard for each of these fingerpieces, thereby necessitating making the guard unduly long. Furthermore, the trigger mechanisms of this character as heretofore constructed necessitated the employment of an unduly large number of parts, increased the cost of manufacture and was liable to derangement of parts.

The objects of this invention are to eliminate the objectionable features in the firing mechanisms above enumerated and to that end the present trigger mechanism is so organized that the firing hammer is arranged in front of the firing trigger and the firing hammer is operated by a forward movement of its fingerpiece and the firing trigger is operated by a rearward movement of its fingerpiece, so that but a single finger or thumb space need be employed between

the two fingerpieces which permits of reducing the length of the guard accordingly and produces a more compact construction. My invention has the further object to simplify the construction of the firing mechanism so as to reduce the number of parts, to reduce the number of machine operations for producing the same and to reduce the liability of any foreign matter entering the interior parts of the trigger mechanism and interfering with the action of the same.

In the accompanying drawings: Figure 1 is a fragmentary side elevation, partly in section, of a breech loading firearm equipped with my improvements and showing the trigger mechanism in its normal or uncocked position. Figure 2 is a similar view showing the position of the parts when the trigger mechanism is cocked and the firearm is ready for firing. Figure 3 is a similar view showing the position of the parts when the firing trigger has been pulled for releasing the sear from the head of the firing bolt. Figure 4 is a fragmentary detached top plan view of the lower or guard section of the frame and the parts mounted thereon, this view being taken substantially on line 4-4, Fig. 2, looking downwardly. Figure 5 is a fragmentary vertical transverse section taken on the correspondingly numbered line in Fig. 1.

Similar characters of reference indicate corresponding parts throughout the several views.

Although my improved firing or trigger mechanism may be organized to suit various forms of firearms, that shown in the drawings, as an example suitable for receiving my improvements, comprises a wooden stock 1, an upper metal frame section 2 secured to the upper part of the stock, a lower metal frame section 3 secured to the lower part of the stock, a longitudinally movable firing pin 4 guided in the upper frame section and provided with a firing head 5 having a forwardly facing bent or shoulder 6 on its underside, and a vertically swinging sear 7 arranged in a recess or chamber 8 in the stock between the upper and lower frame sections and pivoted at its front end to the upper frame section by means of a transverse pin 9. This sear is provided at its rear end with a nose 10 which projects upwardly through an opening or slot 11 in the upper frame section in such position that its rear side may be engaged with the bent

of the firing head. The sear is yieldingly held in its operative position in which its nose is arranged in the path of the bent on the firing head by means of a spring 12 5 operating on a rearwardly projecting arm 13 of the sear.

My improved firing or trigger mechanism which is associated with the above described parts is preferably constructed as follows:

10 Arranged within the longitudinal slot 11 in the upper metal section 2, is the sear 7 which is pivoted by means of the horizontal transverse pin 9. The lower frame section is provided with a longitudinal slot 14, 15 which opens into the lower end of the recess 8 in the stock and upon the upper side of this frame section and arranged along opposite sides of its slot are two longitudinal flanges 15, 15, which are formed integrally 20 with the lower frame section. On its underside the lower frame section is provided with a downwardly projecting guard 16 which extends from the front to the rear end of the slot in this frame section and is 25 formed integrally therewith.

Within the slot 14 and the guard of the lower frame section and the recess 8 of the stock are arranged the main, releasing or firing trigger 17 and the firing hammer 18. 30 The main or firing trigger is arranged at the rear and the firing hammer is arranged in front of the firing trigger. The main or firing trigger is arranged with its central part within the rear part of the slot 14 in the 35 lower frame section and is pivoted thereon to swing vertically by means of a horizontal transverse pin 19, connecting the central part of this trigger with the rear parts of the flanges 15. Below its pivot the firing 40 trigger is provided with a downwardly projecting fingerpiece 20, which is arranged within the rear part of the guard, and above the pivot the same is provided with a trip arm 21, which is adapted to engage its 45 front side with the rear side of the lower rear sear arm 22. Upon moving the fingerpiece of the firing trigger rearwardly, its upper trip arm engages the lower rear sear arm, depressing the rear end of the sear, in 50 opposition to the spring 12, and the nose of the sear is disengaged from the bent of the firing head and thereby permits the firing bolt to be projected forwardly in the usual manner for discharging the firearm. 55 The firing trigger is yieldingly held in position in which its fingerpiece is in the forward position and its trip arm is in its rearward position by means of a spring device, which comprises a transverse finger 23, 60 which engages with an upward facing shoulder 24 formed on the rear trigger. This return movement of the firing trigger under the action of the spring device may be adjusted by means of a stop screw 25, arranged in the lower frame section, as shown 65

in Figs. 1, 2 and 3. On its front side, and at a point below its pivot, the firing trigger is provided with a forwardly and downwardly projecting nose 26, the upper side of which forms a cam-shaped setting face 27, 70 and the lower side of which forms an abrupt catch face 28.

The firing hammer is arranged with its central part in the front part of the slot 14 of the lower frame section, and is pivoted 75 thereon to swing vertically by means of a horizontal transverse pin 29 passing through the central part of this firing hammer and the adjacent parts of the flanges 15. This firing hammer is provided with a downwardly projecting fingerpiece 30 which is arranged within the front part of the guard and the same is also provided with an upwardly projecting trip arm 31 which is adapted to engage its front side with the rear side of the front lower arm 32 of the sear. Between its upper and lower ends the firing hammer is provided on its rear side with a rearwardly projecting nose 33, the underside 80 of which forms a cam-shaped setting face 34, while its upper side forms an abrupt catch face or shoulder 35, which faces are adapted to engage with the cam and catch faces of the firing trigger for setting the firearm preparatory to discharging the same. 85 When free, the firing hammer is turned by means of a spring device in the direction for moving its fingerpiece rearwardly and its trip arm forwardly with a hammer blow against the lower front arm of the sear. The 90 spring device is so organized that it forms part of the spring device which retracts the firing trigger, and in its preferred form the same comprises two coils 36, which are mounted on opposite ends of the pivot pin 105 29 outside the frame flanges 15, as shown in Figs. 1, 2, 3, 4 and 5. The forward movement of the upper spring loop 37 is limited by means of a pair of upright stop lugs 38, 38, which are integral with the frame flanges 110 15, and which are provided on their rear sides with vertical stop faces 39 which are adapted to be engaged by the spring loop 37.

In the normal, uncocked or inoperative position of the firing hammer mechanism, the firearm itself being cocked, as shown in Fig. 1, the firing bolt is in its rear position, the sear is elevated with its nose in front of the bent holding back the firing bolt, the firing trigger is turned by the spring device so that its fingerpiece is in its forward position, and the firing hammer is turned by its spring device so that its finger piece is in its rearward position, and the spring loop 115 is resting against the upright stop lugs with the upper trip arm almost but not quite in contact with the lower front sear arm. For the purpose of setting the firing hammer, 120 preparatory to firing the firearm with this 125 130

device, the fingerpiece of the firing hammer is pressed forward, preferably with the thumb, until its rearwardly projecting nose 33 is drawn below the forwardly projecting nose 5 26 of the firing trigger, which catches and holds the firing hammer in the position shown in Fig. 2. In this position of the parts the trip arm of the firing hammer is withdrawn to a considerable distance from 10 the rearward face of the lower front arm of the sear, and the spring loop 37 has been carried back with it, thus putting the spring under compression. With the parts in this position, a slight rearward pull upon the 15 fingerpiece of the firing trigger will disengage the rearwardly projecting nose of the firing hammer from the forward projecting nose of the firing trigger, which permits the spring loop, then under compression, 20 to throw the trip arm of the firing hammer violently forward, its front face striking the rear face of the lower front sear arm, and the impact of the blow will drive the lower sear arm forward, thus drawing the nose of 25 the sear from its engagement with the bent of the firing head and permitting the firing spring to throw the firing pin forward striking the primer of the cartridge and thus discharging the firearm. The forward movement 30 of the trip arm of the firing hammer is such as to permit it to pass its point of rest, thus its inertia follows up the receding lower front sear arm and makes the blow effective, although the spring loop is checked 35 by the vertical rear faces of the upright stop lugs.

If desired, the firing hammer device may be ignored, as when a heavier pull is desired, or when there is not time to set the 40 firing hammer, and the firearm be fired by a direct rearward pull of the firing trigger. In such case the rearward pull upon the fingerpiece of the firing trigger carries the trip arm of that trigger forward where it 45 engages the lower rear sear arm and a continuation of the pull forces that sear arm downward, thus withdrawing the sear nose from in front of the bent on the firing head and permitting the firing spring to throw 50 forward the firing pin against the primer of the cartridge and explode it.

The extent of the contact between the front nose of the firing trigger and the rear nose of the firing hammer when the mechanism 55 is set, can be regulated by the adjusting screw 25, and as the amount of this engagement controls the amount of force necessary to be applied in order to release the firing hammer, the pull of the trigger may be controlled thereby.

I claim as my invention:

1. A firing mechanism for firearms comprising a firing head having a bent, a sear engaging said bent, a firing trigger oper- 60 atively related to said sear and having a

rearwardly moving fingerpiece, and a firing hammer co-operating with said firing trigger arranged in front of the same and having a forwardly moving fingerpiece.

2. A firing mechanism for firearms comprising a firing head having a bent, a sear engaging said bent, a firing trigger, and a firing hammer located in front of said firing trigger and being operatively associated with said sear for releasing the same from 70 said bent.

3. A firing mechanism for firearms comprising a firing head having a bent, a sear engaging said bent, a firing trigger, a firing hammer mounted in the lower frame section 80 of said firearm in front of said firing trigger and being operatively associated with said sear for releasing the same from said bent.

4. A firing mechanism for firearms comprising a firing head having a bent, a sear engaging said bent, a firing trigger, a firing hammer mounted in the lower frame section of said firearm in front of said firing trigger, a finger piece on said firing hammer 90 depending downward within the trigger guard of said firearm for cocking said firing hammer, and said firing hammer being operatively associated with said sear for releasing the same from said bent. 95

5. A firing mechanism for firearms comprising a firing head having a bent, a sear engaging said bent, a firing trigger, a firing hammer mounted in the lower frame section of said firearm in front of said firing 100 trigger, a finger piece on said firing hammer depending within the trigger guard of said firearm and being integral with said firing hammer for cocking the same, and said firing hammer being operatively associated 105 with said sear for releasing the same from said bent.

6. A firing mechanism for firearms comprising a firing head having a bent, a sear engaging said bent, a front firing hammer 110 having an upper trip arm engaging said sear, a lower fingerpiece and a catch shoulder on its rear side between its arm and fingerpiece, and a rear firing trigger having an upper trip arm engaging said sear, a 115 lower fingerpiece and a catch shoulder on its front side between its arm and fingerpiece and adapted to engage the catch shoulder of said front firing hammer.

7. A firing mechanism for firearms comprising a firing head having a bent, a sear engaging said bent, a front firing hammer having an upper trip arm engaging said sear, a lower fingerpiece, a catch shoulder on its rear side and a spring shoulder on 120 its rear side, a rear firing trigger having an upper trip arm engaging said sear, a lower fingerpiece, a front catch shoulder engaging with the catch shoulder of the firing hammer, and a rear spring shoulder, 125 130

and a spring engaging with the spring shoulders of said firing trigger and said firing hammer and operating to turn said firing trigger and firing hammer so that the fingerpiece of the firing hammer moves rearwardly and the fingerpiece of the firing trigger moves forwardly.

8. A firing mechanism for firearms comprising a firing head having a bent, a sear engaging said bent, a front firing hammer having an upper trip arm engaging said sear and a lower fingerpiece, a rear firing trigger co-operating with said firing hammer and having an upper trip arm engaging said sear and a lower fingerpiece, spring means for turning said firing trigger and firing hammer so that the fingerpiece of the firing hammer moves rearwardly and the fingerpiece of the firing trigger moves forwardly, and means for adjusting the extent of movement of said firing trigger under the action of said spring means.

9. A firing mechanism for firearms comprising a firing head having a bent, a sear engaging said bent, a front firing hammer having an upper trip arm engaging said sear and a lower fingerpiece, a rear firing trigger co-operating with said firing hammer and having an upper trip arm engaging

said sear and a lower fingerpiece, spring means for turning said firing trigger and firing hammer so that the fingerpiece of the firing hammer moves rearwardly and the fingerpiece of the firing trigger moves forwardly, and means for adjusting the extent of movement of said firing trigger under the action of said spring means comprising a screw arranged in rear of the firing trigger and engaging the latter.

10. A firing mechanism for firearms comprising a firing head having a bent, a sear engaging said bent, a front firing hammer having an upper trip arm engaging said sear and a lower fingerpiece, a rear firing trigger co-operating with said firing hammer and having an upper trip arm engaging said sear and a lower fingerpiece, spring means for turning said firing trigger and firing hammer so that the fingerpiece of the firing hammer moves rearwardly and the fingerpiece of the firing trigger moves forwardly, means for adjusting the extent of movement of said firing trigger under the action of said spring means, and a frame on which said firing trigger and firing hammer are pivoted and which has a single slot containing both said trigger and said hammer.

CHARLES NEWTON.
